CLAIM

The ornamental design for a pool or spa vacuum as shown and described.

DESCRIPTION

FIG. 1 is a front, top, left perspective view of a pool or spa vacuum showing my new design;

FIG. 2 is a rear, bottom, right perspective view thereof;

FIG. 3 is rear elevation view thereof;

FIG. 4 is a front elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, top, right perspective view thereof, showing a lower portion of the pool or spa vacuum in a flexed position; and

FIG. 10 is a rear, bottom, left perspective view thereof;

FIG. 11 is a rear, right side elevation view thereof; and,

FIG. 12 is a front elevation view thereof.

The broken lines depict unclaimed features of the pool or spa vacuum that form no part of the claimed design.

1 Claim, 11 Drawing Sheets
